UNITED STATES PATENT OFFICE.

EDGAR H. COTTRELL, OF STONINGTON, CONNECTICUT, ASSIGNOR TO THE C. B. COTTRELL & SONS COMPANY, OF SAME PLACE AND NEW YORK, N. Y.

PRINTING-MACHINE.

SPECIFICATION forming part of Letters Patent No. 541,265, dated June 18, 1895.

Application filed September 29, 1894. Serial No. 524,420. (No model.)

To all whom it may concern:

Be it known that I, EDGAR H. COTTRELL, of Stonington, in the county of New London and State of Connecticut, have invented a new and useful Improvement in Printing-Machines, of which the following is a specification.

This invention relates to printing machines of the kind known as "perfecting" machines in which a tympan on the second impression cylinder is automatically shifted while the said cylinder continues in motion between two successive printings, such shiftings being preferably to the extent or distance necessary to present an entirely fresh clean portion out 10 side of the cylinder. Such provision as has been heretofore made for shifting the tympan to the extent hereinabove mentioned while the machine continued in motion, has been made without any interruption to the feeding of paper to the machine or to the printing, but that involved the necessity of effecting the shifting of the tympan with such extreme rapidity in a fast running machine that it has become a subject for consideration, with a view to increased speed of the machine, whether it 20 would not be better to skip one printing every time it is desired to shift the tympan and by that means to obtain proper time to effect the shifting without injury to the tympan itself or to the shifting mechanism.

In a machine embodying the present improvement, the impression cylinder is so tripped and the feeding of the paper so interrupted every time the tympan has to be shifted as to skip or omit one printing and so obtain ample time for the shifting.

I will proceed to describe my invention in detail and afterward point out its novelty in claims.

Figure 1 represents a side view of as much of a flat-bed perfecting printing-machine as is necessary to illustrate my invention. Fig. 2 represents a horizontal section taken in the line 2 2 of Fig. 1; Fig. 3, a transverse vertical section in the line 3 3 of Fig. 1, looking toward the right; Fig. 4 a transverse vertical section in the line 4 4 of Fig. 1, looking toward the right; Fig. 5, a transverse section in the line 5 5 of Fig. 1, looking toward the right. Figs. 6, 7, 8, and 9 are profile views of cams which will be hereinafter described. Fig. 10

represents an end view of the second impression-cylinder, showing the shifting tympan and parts of its operating mechanism. Figs. 11 and 12 are views at right angles to each other of what is hereinafter termed the "clutch mechanism."

A designates the framing of the machine; A', the feeder's platform; B, the feeding table; B' the feeding cylinder; C', the first impression cylinder; C², the second impression cylinder; F', the first type form; F², the second type form, and D the delivery fly.

I is what is known as the "side shaft," commonly used in flat bed cylinder printing machines for operating certain parts of the machine, arranged in the usual way in bearings inside of one side of the framing, the said shaft being driven at the rate of one revolution to each sheet printed or to each operation of the machine, the cylinders C' and C² making each two revolutions to each complete revolution and operation of the machine. The driving of the cylinders and of the bed which carries the forms may be effected by 65 gearing similar to that which is used in other flat bed perfecting printing machines and therefore I have not thought necessary to represent such gearing and indeed I have only 70 represented the bed by a single line 10 which 75 represents its face.

Above the side shaft I and parallel with it, there is arranged in suitable bearings inside of the framing, a shaft J which I term the tripping shaft and which is to be driven by 80 the said shaft I and for that purpose is geared therewith by gears T and U so proportioned that J may be caused to make one revolution for two revolutions of I, or in other words, one revolution for every two complete revolutions 85 or operations of the machine or for four revolutions of the cylinders C' and C². This tripping shaft J carries several cams for performing the operations of setting the tympan shifting devices in action and of tripping the impression cylinders and feeding apparatus before said shifting action and keeping them tripped as required during said action. As these operations only take place at such times as may be desired after several printings, the 90 driving gear T is fitted loosely to the side shaft I so that it may turn freely thereon at all

other times, and a toothed clutch R is fitted to slide on a feather on the said shaft for the purpose of engaging with corresponding teeth on the hub of the said gear, when the said shaft is required to operate, and of disengaging the said gear at other times. The teeth of the said clutch and hub respectively are made of such different sizes that the gear can only be engaged with the shaft at one point in their respective circumferences. The gear U is fast on the tripping shaft.

Q (Figs. 1, 2, 5, 11 and 12) is a lever swinging on a fixed fulcrum on the side framing A and having on its lower end a fork Q* which engages with the clutch R.

X is a pawl lever hung on a fixed fulcrum 12 on the side framing for the purpose of engaging a hook 13 on the clutch lever Q and thereby holding and locking the clutch R out of engagement with the gear T and leaving said gear inoperative upon the shaft J.

Q' is a pushing spring applied to the clutch lever Q for the purpose of pushing the clutch R into engagement with the gear T and coupling the said gear with the side shaft I when the pawl lever X is raised out of engagement with the hook 13 on the clutch lever.

P is a cam on the tripping shaft J for operating on the said lever Q to throw the clutch R out of engagement with the gear T.

V and W are what I call tripping gears. The gear V is fast on the side shaft I and has affixed firmly to one side of it a tappet 14 (see Fig. 5) having a beveled end. The gear W is loose on the tripping shaft J and is fitted with a tappet 15 which is fitted to slide radially in a guide 16, in the side of the said gear. The outer end of the tappet 15 is beveled the reverse of the outer end of the tappet 14. The said tappet 15 has applied to it a spring 17 to force it outward from the shaft J. One of the tripping gears V and W, which run together, has one more tooth than the other, the number of teeth depending on the number of revolu-

tions of the side shaft and corresponding number of operations of the machine it is intended to make and the number of printings to be performed before the shifting of the tympan. In the example represented the shifting is to be performed once during every one hundred operations of the machine or after every ninety ninth printing and therefore the gear V on the side shaft I has ninety-nine teeth and the gear W on the tripping shaft J, one hundred teeth. At every one hundredth revolution of the gear V, the tappet 14 on the said gear meets the sliding tappet 15 on the gear W and pushes it upward so far that its upper end acting against a projection

18 on the pawl lever X, lifts the said lever out of engagement with the hook 13 on the clutch lever Q and so leaves the said lever free to the action of the spring Q' which pushes the said lever in the direction to throw the clutch R into engagement with the gear T and to engage the said gear with the tripping shaft J, and so set the latter shaft in motion,

but this motion only continues to the extent of one revolution of the tripping shaft for at the end of one revolution the cam P by its action on the clutch lever Q, disengages the clutch R and liberates the gear T. The hook 13 on the clutch lever then passes under and lifts the pawl lever, after which the latter lever drops into the said hook and locks the clutch lever and keeps the clutch disengaged until the next operation of the tappets 14, 15 on the tripping wheels.

In order that the cam P may be made to escape from the lever Q after having thrown the clutch out of engagement and thereby permit the spring Q' to produce the re-engagement of the clutch at the proper time, the said cam is not rigidly attached to the shaft J but is so attached thereto that it may turn thereon a short distance, the cam itself being a portion of a disk which is fitted loosely to the shaft and attached to a flanged hub P' which is fast on the shaft. The attachment to the said hub P' is represented as made by screws 50 passing through slots 51 in the cam disk and screwing into the flange of the hub. A spring 52 coiled upon the shaft and having one end fastened to the shaft and the other end fastened to the cam disk tends to turn the cam upon the shaft in the same direction in which the shaft itself turns, but when the cam comes in contact with the roller provided for it on the lever Q which is just before it is required to operate on the lever, the resistance which it meets with causes it to stop until the screws 50 reach the forward ends of the slots 51 and carry the cam forward till its most prominent point meets the roller on the lever and completes the movement of the latter and effects the disengagement of the clutch. The cam then meeting with very little resistance is quickly turned forward on the shaft by the spring 52 far enough to leave the lever free to be operated by the spring Q' to engage the clutch.

The journal boxes a', a² of the cylinders have applied to them respectively the lifting rods b', b², and springs c', c² common to the cylinders of two revolution flat bed printing machines for lifting the said cylinders and the said rods have applied to them the usual yokes E', E² and toggles G', G² for depressing said cylinders for printing. These toggles G', G² are operated in the usual way by rock-shafts H', H² which are operated by gab hooks S', S² carried by a lever S¹ S² which swings on a fixed pivot S, the said lever receiving motion through a rod S³ from a cam S⁴ on a rotary shaft S⁵ arranged transversely of the machine and driven in the usual manner, the operation of the said gab hooks being such, while the printing is regularly proceeded with, that the cylinders are depressed alternately one being raised when the other is depressed.

For the purpose of lifting the gab hooks I employ two rock-shafts Y' Y² arranged transversely to the machine in suitable bearings in the lower part thereof. These rock-shafts

may be and are represented as the same as have been commonly employed for operating the "trip-at-will," the said rock-shafts being furnished respectively with lifting arms d' d^2 which are situated under the gab hooks as shown in Figs. 1 and 2. The rock-shaft Y' belonging to the first impression cylinder C' is furnished with another arm 19 which is connected with the trip-at-will rod C'^* and the rock-shaft Y^2 belonging to the second impression cylinder C^2 , is furnished with an arm 20 which is connected by a rod 21 with an elbow lever 22 on the outside of the framing, the other arm of the said lever being connected with the trip-at-will rod C^2* . For the purpose of tripping the cylinders automatically at the times when it is desired to skip printing and to shift the tympan, the tripping shaft J is furnished with two cams, viz: one K' (Figs. 1, 2 and 4) for tripping the first impression cylinder C' and one K^2 (see Figs. 1, 2 and 3) for tripping the second impression cylinder C^2 . The yoke rod e' of the cam K' is connected with one of the arms f' of the rock-shaft Y' and the yoke rod e^2 of the cam K^2 is connected with one of the arms f^2 of the rock-shaft Y^2 .

The same cams K' and K^2 on the tripping shaft and the same rock-shafts Y' and Y^2 which trip the two impression cylinders, trip at the same time the form rollers $g' g^2$ of the inking apparatus for the corresponding forms $F' F^2$. The connections between the said rock-shafts and the frames of the form rollers consist respectively of levers $h' h^2$ (see Fig. 1) which are fulcrumed on the inside of the side framing, rods $i' i^2$ which connect the said levers at one end respectively with the two form roller carriages $Z' Z^2$ and rods $j' j^2$ which connect the other ends of the said levers with the arms $f' f^2$ of the respective rock-shafts Y' and Y^2 . The above described connections between the rock-shaft Y^2 and the form roller carriage Z^2 are shown in Fig. 3. There is also on the tripping shaft J , a cam L (see Figs. 1, 2, 4, and 6) for throwing the grippers of the feeding cylinder B' out of operation at the times when the feeding is to be intermittent and the printing skipped for shifting the tympan, the said cam operating through the upright spindle 23 arranged in bearings 23* outside of the framing. This spindle 23 is furnished on its upper part with arms 24, 25, for drawing back the sliding pins 26, 27, provided in the upper part of the framing for operating the tumbler cam k (Fig. 1) of the feeding cylinder grippers, the said spindle being actuated by the said cam L (as shown in Fig. 2) through a connection between the yoke rod 28 of the cam and an arm 29 on the said spindle. The said spindle 23 and the pins 26, 27 and their connections do not, however, of themselves constitute parts of the present invention except as to their connection with the tripping shaft J , and as with that exception they are well understood, they need no further illustration or description

here beyond saying that the ordinary means of operating them by the side shaft I at the proper time during every revolution of the machine are retained in carrying out my invention, such means consisting of a cam L^* (see Figs. 1 and 4) on the said shaft I and a connection between the yoke rod 30 of said cam and an arm 31 on the lower end of the said spindle. The pins 26, 27, are returned to their operative positions after the passing by of the cams L L^* , by a coil spring 32 which surrounds the said spindle and one end of which is fast to the spindle and the other to one of the bearings 23*. There is furthermore provided on the tripping shaft J , a cam L^2 for drawing back and rendering inoperative the sliding pin 33 (see Fig. 1) commonly provided for turning the tumbler cam l of the gripper shaft of the second impression cylinder C^2 to produce the closing of the grippers of the said cylinder C^2 to take the sheet. This cam L^2 operates through an upright spindle 34 which is fitted to fixed bearings 35 outside of the framing and which has an arm 33* connected with the said pin, the said spindle being similar to the one commonly used in flat bed perfecting machines for the purpose of interrupting the operation of the grippers of the second impression cylinder during every other revolution thereof for which latter purpose it is actuated by a cam L^3 (see Figs. 1 and 3) on the side shaft I. The cam L^3 on the side shaft operates on the said spindle 34 through a connection of its yoke rod 38, with an arm 39 on the lower end of said spindle; and the cam L^2 on the tripping shaft operates on the said spindle through a connection of its yoke rod 40 with an arm 41 on the said spindle. The said pin 33 is returned to its operative position by means of a spring 42 which surrounds the spindle 34 and which has one end attached to the spindle and the other to one of its bearings 35.

Besides the cams K' K^2 L L^2 hereinabove described on the tripping shaft J , there are also two other cams, viz: one M (Figs. 1, 2, 3 and 8) for throwing the automatic tympan shifting mechanism into operation and another N (Figs. 1, 2 and 9) for throwing out of operation that part of the feeding mechanism by which sheets are supplied to the feeding table B whence they are taken by the grippers of the feeding cylinder B' to be given to the first impression cylinder.

The cam M for throwing the tympan shifting mechanism is represented as acting upon a lever 43 (Fig. 3) which is fulcrumed on the side framing and which is represented as connected by a rod 44 with one arm 46 of a rock-shaft 45 (see Fig. 1) arranged in suitable bearings transversely to the machine, the said rock-shaft having a similar arm 46 (see Fig. 10) which is connected by a rod 46* with the device for throwing the tympan shifting mechanism into operation. The last mentioned device and the tympan shifting mechanism do not constitute parts of this invention but

they may be for example, such as are the subject-matter of United States Patent No. 467,637, dated January 26, 1892, and for the sake of illustration I have so represented them in Fig. 10 with reference to which figure I will describe them as far as is necessary to explain the present invention.

54 designates the web of paper of which the tympan is composed and which is supplied from a roller 55 and shifted and taken up by rollers 56, 57, 58, all within the cylinder, the shifting and taking up being effected by a spur gear 59 on the roller 57 gearing with a stationary gear 60, and the letting off from the supply roller being controlled by a pawl lever 61 operating on a ratchet wheel 62 on the latter roller.

63 is a locking lever which locks the shifting mechanism in an inoperative condition. 20 This locking lever which is fulcrumed on the side framing, is the same as the locking lever shown and described in the hereinabove mentioned patent and as the intervening mechanism between said locking lever and the feed rollers 56, 57 and pawl lever may also be the same as is described in that patent, I have not thought it necessary to represent it. The rod 46* is, as shown in Fig. 10, connected with the locking lever 63 by means of a bell-crank 25 64 fulcrumed on the side framing and a rod 65. When the cam M comes into operation it lifts the lever 43, rod 44 and the arms 46 of the rock-shaft 45 and so by means of the rod 46*, bell-crank 64 and rod 65 actuates the 30 locking lever to set the tympan shifting mechanism in operation.

I propose generally to employ a mechanical feeding apparatus for feeding the sheets to the feeding table B, but as this apparatus 40 may be of any known or suitable kind and as it forms no part of the present invention I have not thought it necessary to represent any more of it than its shafts *m* *n* and the gearing for driving them from the feeding cylinder B' which has a constant rotary motion. This cylinder B' is furnished with a bevel gear *p* which gears with a bevel gear *q* on a shaft *q'* (Fig. 1) which is arranged in suitable bearings on the side framing A and 45 at the other end of which is a bevel gear *q*² gearing with a bevel gear *q*³ which turns on a fixed stud *q*⁴ on the framing. This bevel gear *q*³ has fast to it a spur gear *q*⁵ which gears with a spur gear *m'* on the shaft *m* of the feeding apparatus. The shaft *q'* is divided into two lengths or sections which are 50 united by a clutch *r* *r'*, one member *r* of which is fast to one of said sections and the other member *r'* is fitted to slide on a feather 55 60 on the other section. A spring *r*² surrounds the shaft between the sliding clutch member *r'* and a collar *r*³ on the shaft and acts to keep the clutch in engagement and the two sections of the shaft coupled. The cam N 65 (Figs. 1, 2 and 9) is for uncoupling the shaft *q'* and for that purpose its yoke rod *N** is connected with one arm *s* of an elbow lever

which works on a fixed fulcrum on the side framing and the other arm *s'* of which engages with the sliding clutch member *r'*.

70 While the machine is in regular operation the clutch *r* remains coupled and the shaft *q'* drives the shaft *m* of the feeding apparatus, but when the time arrives for shifting the tympan and the tripping shaft J is thrown 75 into gear with the side shaft, the cam N throws the sliding member *r'* of the clutch out of engagement and uncouples the shaft *q'* and so produces the cessation of the operation of the gears *q*² *q*³ *q*⁵ and stops the supply of sheets. 80

Having now described the construction and separate operations of the several parts of the mechanism involved in the carrying out of my invention, I will now describe briefly the 85 succession of operations for producing the permissions of the feeding and printing, preparatory to and during the shifting of the tympan.

The predetermined number of revolutions and complete operations of the machine without shifting the tympan having taken place and the tappets 14, 15 of the tripping gears V W having come together, the first operation is the liberation of the clutch lever Q and the throwing of the clutch R into engagement with the gear T on the side shaft I by the action of the spring Q' which causes the tripping shaft J to make one revolution during the next two revolutions of the side shaft I as hereinbefore explained. Then the bed 90 and forms being in their return movement (viz: to the right hand in Fig. 1) and the first impression cylinder C' having been tripped in the usual way by action of the cam S⁴ and raised by its springs c' c' as hereinbefore described, the cam K' comes into operation before the outer end of the first form F' reaches either of the first form rollers g' g', and the said cam acting through the rock-shaft Y' lifts the gab hook S' and so leaves the first 95 impression cylinder lifted and at the same time lifts the said form rollers. At about the same time the cam L acting on the upright shaft 23 draws out the pins 26, 27, and so prevents the grippers of the feeding cylinder B' 100 from taking the next sheet until the machine has made a complete revolution, or in other words, causes the cylinder to skip a sheet or miss taking one until the next revolution. When the machine has made about half a 105 complete revolution, the cam K² acting through the rock-shaft Y², lifts the gab hook S² and leaves the second impression cylinder C² raised by the springs c² c² and at the same time raises the form rollers g² g² of the said 110 cylinder out of the way of the second form F². At this time or before the tripping cam l of the second impression cylinder C² reaches the pin 33, the cam L² acting upon the upright shaft 34 draws out the said pin 33, and prevents the grippers of the latter cylinder from 115 closing at that point where they would take a sheet from the first impression cylinder C' in the regularly repeated operation of print- 120 125 130

ing. The cylinder C' has, however, no sheet at this time, it having received none from the feeding cylinder B' whose gripper motion was tripped as just described. At about this same time also the cam M lifts the lever 43 and throws the tympan shifting mechanism in the cylinder C² into operation and as the grippers are left open, the time occupied in shifting the tympan may be about a whole revolution of the cylinder C². When the machine has made a complete revolution and the tripping shaft J has made a half revolution from the time when the cam K' lifted the gab hook S', the said cam allows the said hook to drop into its operative position, and the cam L which held out the pins 26, 27, will have turned out of the way and will allow the cam L² on the side shaft I to operate as usual so that the grippers of the feeding cylinder B' will take the next sheet. About half a revolution of the machine later the cam K² allows the gab hook S² to drop into its operative position and the form rollers g² g² to drop into their normal positions, and the cam L² which operates on the upright shaft 34 will have turned out of the way. At this time the re-setting cam P operates on the clutch lever Q and takes the clutch R out of engagement with the gear T and the tripping shaft J stops running. The operation is now completed and the clutch R is locked out of engagement by the locking lever X dropping into the hook 13 on the clutch lever until the tappets 14, 15, again meet when the operation is repeated.

It will be understood that by the tripping of the cylinders and the form rollers and the stoppage of the feed as hereinbefore described by the cams on the tripping shaft J, on which also is the cam for throwing the tympan shifting mechanism into operation, all the functions of the printing machine except the shifting of the tympan are suspended during one complete revolution of the machine and that the tympan is shifted during that revolution.

The means herein described of tripping the cylinders and form rollers when the printing is to be skipped and of controlling the shifting of the tympan may be employed while the machine is fed by hand, the hand feeder in such case not presenting any sheet while the tripping shaft J remains in gear with the side shaft. For a machine which is to be fed by hand and in which no mechanical feeding apparatus is provided, the cams L and N on the tripping shaft and the mechanism through which they operate would be omitted, but all the other cams and operative devices on and in connection with the said shaft J would be retained.

It is obvious that in carrying out my improvement I am not necessarily confined to the particular mechanism herein described for effecting the suspension or intermission of the feeding and printing operations during one complete revolution of the machine in which the shifting of the tympan takes place but that such mechanism may be con-

siderably varied without departure from my invention.

Although it may be preferable in carrying out my invention that every time the tympan is shifted it should be shifted to the whole extent or distance necessary to present an entirely fresh or clean portion outside of the cylinder, the shifting a part of such distance only might be performed during one such skipping or intermission of the printing as is herein described and the completion of the shifting performed during another such intermission or skipping.

What I claim as my invention is—

1. In a perfecting printing machine one impression cylinder of which is provided with an automatically shifting tympan, the combination with said cylinder, of mechanism for tripping it and means for controlling the operations of said tympan and of said tripping mechanism substantially as herein described whereby the said cylinder is rendered inoperative from time to time during a complete revolution of the machine and the tympan is shifted while the cylinder is so inoperative.

2. In a perfecting printing machine, the combination with an impression cylinder which is provided with an automatically shifting tympan, and a feeding apparatus for said machine, of automatic means for controlling at the same time the shifting of said tympan and the operation of the feeding apparatus substantially as herein described whereby the feeding apparatus is rendered inoperative from time to time during a complete revolution of the machine and the tympan is caused to be shifted during that revolution.

3. In a perfecting printing machine, the combination with an impression cylinder which is provided with an automatically shifting tympan, mechanism for tripping said cylinder, and a feeding apparatus for said machine, of means for controlling the shifting of said tympan and the operations of said tripping mechanism and feeding apparatus substantially as herein described whereby the feeding apparatus and the cylinders are rendered inoperative from time to time during a complete revolution of the machine in which the tympan is shifted.

4. In a perfecting printing machine one of the cylinders of which is provided with an automatically shifting tympan, the combination with a continuously rotating shaft and a cam shaft furnished with a cam for throwing the shifting mechanism of said tympan into operation, and gearing through which said cam shaft may be driven by said continuously rotating shaft, of mechanism substantially as described actuated by said continuously rotating shaft for throwing said gearing into and out of operation from time to time as and for the purpose herein set forth.

5. In a perfecting printing machine having a mechanical feeding apparatus and one of the cylinders of which is provided with a

shifting tympan and means for automatically shifting the same, the combination of a continuously rotating shaft, a cam shaft, a cam on said cam shaft for throwing the feeding apparatus out of action, a cam on said cam shaft and tripping mechanism controlled by said cam for tripping said impression cylinder and a cam on said shaft for throwing the tympan shifting mechanism of said impression cylinder into operation, gearing through which said cam shaft may be driven by said continuously rotating shaft, and mechanism substantially as herein described actuated by said continuously rotating shaft for throwing said gearing into and out of operation as and for the purpose herein set forth.

6. The combination of the constantly rotating side shaft I and the intermittently rotat-

ing cam shaft J, the gears T U one fast on the shaft I and the other loose on the shaft J, 20 the clutch R on the shaft I, the clutch lever Q, the spring-controlled cam P on the shaft J and the pushing spring Q' for operating said lever and clutch to engage and disengage the loose gear T with and from the shaft I, the 25 pawl lever X for locking the clutch lever Q, the differentially toothed tripping gears V W on the shafts I J, the tappet 14 on the gear V and the sliding tappet 15 on the gear W for actuating said pawl lever to liberate the 30 clutch lever, all substantially as and for the purpose herein set forth.

EDGAR H. COTTRELL.
